UNITED STATES PATENT OFFICE.

EDWIN S. PEARCE, OF INDIANAPOLIS, INDIANA.

METHOD OF AND APPARATUS FOR IMPREGNATING FIBROUS MATERIALS WITH LIQUIDS.

Application filed February 17, 1925, Serial No. 9,899. Renewed September 1, 1927.

My invention relates to methods of and apparatus for impregnating fibrous materials with liquids.

The invention is particularly adapted for employment in the impregnation of fibrous waste, for example, cotton, wool, mixtures of these, or other suitable fibrous material with oil or grease for use as journal box packing for lubricating the journals of shafts, rail-
way car axles and the like, but the said invention is of great value and utility for use in the impregnation of fibrous materials of various kinds with liquids. For example, it may be used to great advantage in the impregnation of cotton, wool, silk and other like fibrous materials with liquid dyes in the operation of dyeing the same. Other uses and purposes of the invention will suggest themselves as the description proceeds and also will suggest themselves to those skilled in the art to which the invention relates.

The invention will be described with relation to its use for effecting the impregnation of fibrous waste with liquid lubricants, such as oil or grease, for use as a journal box packing. It will be understood, however, that the principal of operation enunciated and described herein is the same whether the apparatus and the method be employed for that purpose or for other purposes to and for which the invention may be adapted.

The invention is adapted for use in the treatment of either new waste fibrous material, of fibrous material which previously has been used as journal box packing but which has been cleaned, or a mixture of previously used cleaned fibrous material and new material, and also for use in dyeing operations as above indicated.

The general object of the invention is to provide a novel apparatus and method by the employment of which fibrous materials may be more completely and uniformly impregnated with a liquid, such as oil, than heretofore has been practicable; and to effect such impregnation most economically.

It also is an object of the invention to provide a method and an apparatus by means of which the entire quantity of liquid lubri-

cant, such as oil, or other liquid, calculated to be necessary to saturate completely a given quantity of waste or other material may be completely absorbed within and by the said material.

Another object of the invention is to provide an apparatus of novel construction including means whereby a batch or mass of immersion of the fibrous material within the impregnating liquid may be effected gradually and at a rate or speed in proportion to the normal release and escape of air from the batch or mass or in step with the normal uniform rise of the liquid in the batch or mass.

The foregoing are some of the objects of the invention but it will be understood that there are many other objects and advantages incident to the invention which will be pointed out in the detailed description thereof which follows or will become apparent from such description.

An understanding of the invention may be facilitated by reference to the accompanying drawings in which I have shown one convenient form of apparatus by means of which the method may be economically practised, which apparatus embodies certain novel features of construction, as will be pointed out hereinafter in detail in the specification and particularly set forth in the claims.

In the drawings:

Fig. 1 is a view in vertical section of an apparatus embodying novel features of construction and by the employment of which the method may be practised;

Fig. 2 is a view partly in side elevation and partly in vertical section of the apparatus shown in Fig. 1;

Fig. 3 is a transverse sectional view taken on the line 3—3 of Fig. 1; and

Fig. 4 is a transverse sectional view taken on the line 4—4 of Fig. 1.

Before proceeding to a description of the apparatus disclosed in the drawings I shall refer briefly to the principle underlying the invention. One of the reasons why it is difficult to effect complete saturation of

waste fibers or other fibrous material with oil or the like and with liquids which are not oily or oleaginous is that the minute cells and interstices thereof are filled with air, which if present blocks the entry of the said liquids thereinto. If a mass of fibrous material and a liquid lubricant or other liquid are brought into contact or association within a receptacle and the air with-
drawn therefrom; or if they be brought into contact or association within a receptacle from which the air or other gas already has been exhausted or partially exhausted, it will be found that the liquid lubricant or other liquid will enter into the minute cells and interstices and quickly effect saturation of the said fibers. Hence one of the features of my invention is the provision of an apparatus which is adapted to facilitate the contact or association of the liquid lubricant, such as oil or grease, with the fibers under the conditions above indicated; or to facilitate the contact or association of liquid dyes with the fibrous material which is being dyed.

Referring now to the drawings, it will be noted that I have provided a tank or receptacle 1 from the upper edges of which extensions or continuations 2 are provided. For the purpose of closing the tank I have provided a piston comprising a top 3, a depending annular wall 4 having inwardly extending flanges 5 and 6, and a sealing packing 7. The inner lower edge portion of the sealing packing 7 extends underneath the outer edge portion of the part 3 of the piston structure and is clamped between the same and the flange 6 by means of bolts 8. A wire net or screen 12 is secured to the under side of the flange 5 by means of bolts and washers 15. A tubular housing is provided at the central portion of the piston structure which extends a considerable distance above the said piston and is connected to the portion 3 thereof and to the screen. The said housing comprises two sections, 16 and 17. The lower end of the section 16 extends through a central opening in a member 18. The said member is secured to the section 16 by welding or in any other suitable manner and constitutes in effect a flange upon the lower end portion of said member. The member 16 projects upwardly through a central opening 20 in the screen 12 and the flange-like member 18 is secured to the latter by means of bolts and nuts and washers 21. The upper end portion of the section 16 of the housing is screw threaded and is provided with a flanged nut 22 the upper side of which is seated against the under side of the portion 3 of the piston around a central opening 23 therethrough. The screw threaded lower end portion of the section 17 is provided with a flanged nut 24 the lower side of which rests upon the upper side of the part 3 of the piston structure surrounding the said opening 23. These flanged nuts are clamped together and against the opposite sides of the portion of the part 3 surrounding the opening 23 by means of rivets 25. The upper end of the section 17 is closed by means of a screw threaded cap 27. The section 16 of the housing is provided with a series of openings 30 which are located immediately below the flanged nut 22. It will be seen that by means of the tubular housing the screen 12 and the part 3 of the piston structure are firmly and rigidly bound together.

For the purpose of raising and lowering the piston to open and close the tank or receptacle I have provided the piston with a number (four in the present case) of small lugs or brackets 31 having holes or openings through the inner ends thereof with which the lower ends of straps 32 are connected. The upper ends of these straps are connected through openings 33 with the lower outer edges of a member 34 by means of which connection is effected between the straps 32 and the lower end of an elevating rope or cord 35. The member 34 has swivel connection with the lower end of the elevating rope or cord 35. The said cord or rope 35 extends over pulleys 36 and 37 which are mounted upon shafts 38 mounted in bearings supported upon the angle members 40 the opposite ends of which are supported upon the upper ends of vertical standards or supports 42 which are secured to the outer side of the receptacle 1 and to the outer sides of the upwardly extending projections or extensions 2. Secured to the outer depending end of the cord or rope 35 is a weight 45 which counterbalances and tends to elevate or lift the piston 3.

When it is desired to place or insert fibrous material, such as waste, to be saturated with a liquid lubricant such as oil, or other liquid, the piston is elevated so that the lower edge portion of the depending wall 4 is carried to a position above the edge 50 of the tank or receptacle 1 so that the material may be inserted between the lower side of the piston and the top edge 50 of the tank or receptacle. The liquid lubricant or other liquid may be delivered into the tank or receptacle either before or after the placing of the fibrous material therein.

The material having been inserted into the tank the piston is then lowered to such position that the top of the tank or receptacle is closed by contact of the outer upper edge portion of the sealing packing 7 with the inner sides of the upper edge portion of the tank or receptacle.

The method embodying my invention may be carried out in different ways, that is, the

order of the steps employed in the carrying out of the invention may be changed or varied.

One way of carrying out the method embodying and involving my invention is to place the fibrous material within the tank, or receptacle, lower the piston as described, and then exhaust the air to a greater or less extent to create a partial vacuum within the tank or receptacle which operates to remove partially from the minute cells and interstices of the said material the air and any other gases which may be present therein. During this period the piston preferably should be held in the position as shown in the drawings. For conveniently holding the piston in such position I have provided an eye or loop 51 upon the inner side of the lower end portion of the weight 45 which is adapted to be engaged by a hook 52 pivoted near the lower end of one of the supporting posts or standards 42.

For the purpose of removing the air and any other gases which may be present from the tank or receptacle 1 and from the cells and interstices of the fibrous material I have provided a pipe 55, the upper end of which extends upwardly within the tank as indicated in Fig. 1 and the lower end of which is mounted within an opening 57 in the bottom of the tank or receptacle and communicates with a pipe 58 which has connection with an exhaust pump 59 of any desired known construction.

Mounted in an elevated position with respect to the tank or receptacle 1 is a tank or receptacle 60 which is adapted to receive a supply of liquid lubricant, such as oil or grease, or other liquid 61. A pipe 62 is connected at its upper end in an opening in the bottom of the tank 60 and its lower end terminates in a pipe frame 63 from which rise, in the construction shown, four short pipes 64 which project through openings in the bottom of the tank 1. These openings are covered by wire nets or screens 65 which are secured to the bottom of the tank or receptacle 1. The pipe 62 is provided with a valve at 66 by means of which it may be opened and closed.

The fibrous material, which may be waste, as above indicated, having been placed within the tank or receptacle 1, the piston closed to the position as indicated in Fig. 1 of the drawings, and the air and other gases which may be present having been partially removed from the tank, and the proper quantity of liquid lubricant for saturation of the waste having been placed in the tank 60, the valve at 66 is opened whereupon the oil flows quickly from the receptacle 60 into the tank or receptacle 1. The flow is greatly accelerated by reason of the fact that the air and other gases may have been partially evacuated from the tank or receptacle 1.

As already indicated, the fibrous material which is treated may not be waste material to be employed for use as journal box packing but may be fibrous material of any other character.

The liquid lubricant, such as oil or grease, having entered the tank 1 the valve at 66 is closed whereupon the hook 52, if previously engaged with the eye or loop 51, is released therefrom and the operation of the pump 59 begun so as to further remove the air or gases from the tank 1. Upon release of the hook 52 from the eye or loop 51, the piston moves downwardly in the tank or receptacle 1. The further removal from the tank or receptacle 1 of the air or other gases which may be present therein causes and facilitates downward movement of the piston due to the external atmospheric pressure thereon. The result is that the screen 12 presses upon the fibrous material previously placed in the tank and forces it down into the body of liquid lubricant (or other liquid) within the tank. As the further evacuation of the air and gases from the tank or receptacle 1 continues the piston continues its descending movement. The rate at which the air and other gases are withdrawn or evacuated from the tank or receptacle should be such as to cause the piston to descend at a rate proportional to the normal release and escape of air and other gases from the fibrous material within the tank or receptacle. The ideal condition in operation would be that in which, as the fibrous material descends in the oil, all of the air and gases in said material would be displaced so that only that portion of the material above the level of the oil would contain any air or gas. A gage is provided at 70 to indicate the pressure within the tank 1 in order that the percentage of evacuation of the air and other gases therefrom may be indicated.

Instead of following the steps in the order as above explained the piston may be moved to open position and the requisite quantity of liquid lubricant, such as oil or grease, or other liquid, as has been indicated, delivered from the tank 60 into the tank or receptacle 1, after which the fibrous material to be saturated is inserted into the tank or receptacle 1 on top of the said liquid. This method or way of procedure is that which at present is preferred by me. The valve at 66 should then be closed or may be closed before the introduction of the fibrous material into the tank or receptacle 1. Thereafter the piston is moved down into position to close the upper end of the tank or receptacle 1, after which operation of the exhaust pump 59 is begun. The exhaustion of the air and other gases which may be present facilitates and causes downward movement of the piston, under the influence of external air pressure and the force of

gravity, to cause a submersion of the waste material within the liquid lubricant. The exhaustion of the air and other gases which may be present from the minute interstices 5 and cells of the fibrous material, whether said material be waste or of other character, facilitates and causes the ready entry of the liquid lubricant or other liquid into the said interstices and cells. As has been indicated above, the rate at which the air and other gases are withdrawn or evacuated from the tank or receptacle 1 should be such as to cause the piston to descend at a rate proportional to the normal release 10 and escape of air and other gases from the fibrous material. If the batch of fibrous material were caused to descend too rapidly through the liquid lubricant (or other liquid) it might entrain and entrapp 15 in the interstices, cells or pockets present therein, bubbles or globules of air which thereafter might not be released at all, or the release and escape thereof might take place very slowly, thereby necessitating a longer period 20 for the treatment of a given quantity of material.

By causing the immersion of the fibrous material in the liquid lubricant, such as oil (or other impregnating liquid), at a rate proportional to the normal release and escape of the bubbles or globules of air (or other gases, if any be present) from the batch or mass of fibrous material or in step with the normal uniform rise of liquid in 30 the batch or mass, a more complete removal of the air and other gases which may be present from the said mass is brought about and a more complete impregnation thereof with the liquid lubricant or other liquid is effected. It is important to avoid the entrapment and entraining of bubbles or globules of air or other gases within the mass of fibrous material as it descends into the impregnating liquid, such as oil.

Immersion of the fibrous material within the liquid is effected quietly and without appreciable agitation of the said liquid.

The method also may be carried out by placing the fibrous material within the tank 50 or receptacle 1, thereafter closing the piston and thereafter exhausting the air and other gases from the said tank or receptacle as completely as may be practicable, and thereby causing the piston to descend 55 to compress the fibrous material into a layer of greater or less thickness upon the bottom of the tank or receptacle 1. This having been done the valve at 66 may be opened to allow the liquid lubricant (or other liquid) to flow from the tank 60 through the pipe 62 and extensions 64 having connection therewith into the said tank 1. The impregnating process is assisted by the fact that the incoming liquid will be 65 driven upwardly through the fibrous mate-

rial by a pressure in pounds corresponding and in proportion to the percentage of vacuum in the tank or receptacle 1 which may have been obtained and maintained by the exhaust pump 59. After all of the liquid 70 has been discharged from the tank 60 the valve 66 is closed and the operation of the exhaust pump 59 resumed so as to further increase the percentage of vacuum within the tank 1 which had been decreased by 75 the introduction of the liquid lubricant (or other liquid) thereinto.

No matter in what order the steps of the process or method may be carried out the volume of the chamber within the tank or 80 receptacle 1 underneath the piston is gradually decreased during the operation.

By the employment of the method embodying my invention given quantities of waste fibrous material may be caused to 85 completely absorb the amount of liquid lubricant calculated to be necessary to effect complete saturation thereof in a very short time, to wit, within a few minutes; or if the method be employed in the operation 90 of dyeing fibrous materials the period required to effect complete impregnation of said materials with the liquid dye employed is greatly shortened.

It will be seen that my invention not only is 95 simple but that it also is efficient in operation.

The term or word "oil" wherever employed in the specification and claims is intended to include not only what ordinarily is known as oil but also grease of a character which may be used for the saturation 100 of fibrous materials to produce a journal packing.

Having thus described my invention, what I claim and desire to secure by Letters Pat- 105 ent is:

1. The method of impregnating fibrous material with a liquid, which comprises the bringing together of said material and a liquid in a partial vacuum to effect mixing 110 of the same and progressively increasing the vacuum during the process of mixing and impregnation.

2. The method of impregnating fibrous waste material with oil, which comprises the 115 submersion of the waste in and by the oil in a chamber from which the air has been partially evacuated, continuing the evacuation of the air from the chamber after such submersion and varying the volume of said 120 chamber during the period in which impregnation is effected.

3. The method of impregnating fibrous waste material with a lubricating oil to produce journal packing, which comprises the combining of the said waste material and the oil in a chamber from which the air and other gases have been partially evacuated, continuing the evacuation of air and other gases after the combining of the said 130

- waste material and the oil, varying the volume of said chamber, and simultaneously exerting pressure upon the top of the mass to compel submersion of the fibrous material in said oil. 5
4. The method of impregnating fibrous material with lubricating oil, which comprises the introduction of the fibrous material into a chamber, partially evacuating the air from said chamber, introducing oil into the said chamber, thereafter effecting further evacuation of the air from said chamber and simultaneously varying the volume of said chamber. 10
5. The method of impregnating fibrous material with oil to produce a journal packing, which comprises the introduction of said fibrous material into a chamber, withdrawing air and other gases therefrom and varying the volume thereof, and thereafter introducing a predetermined quantity of oil into the bottom of said chamber. 20
6. The method of impregnating fibrous material with oil to produce a journal packing, which comprises the introduction of a predetermined quantity of fibrous material into the top of a chamber, closing the top of the said chamber with a movable closure, retaining said closure in stationary position 25
- and simultaneously withdrawing air from the said chamber, introducing a predetermined quantity of oil into said chamber, releasing said closure, and effecting further withdrawal of air from said chamber. 30
7. The method of impregnating fibrous material with oil to produce a journal packing, which comprises the introduction of said fibrous material into a chamber, closing the opening into said chamber through which the fibrous material is introduced 35
- thereinto, exhausting air and other gases from said chamber and effecting pressure automatically and simultaneously upon the said fibrous material to compress the same against the bottom of the tank the interior of which constitutes the said chamber, and thereafter permitting oil to enter said chamber from the bottom. 40
8. The method of impregnating fibrous material with oil to produce a journal packing, which comprises the introduction of fibrous material into the chamber of a receptacle through the open top thereof, moving a closure into the said open top to close the same, withdrawing air and other gases from the said chamber and causing inward movement of the said closure to compress fibrous material within the said chamber upon the bottom of the said receptacle, simultaneously introducing oil into the said chamber and continuing the operation of withdrawing air and other gases therefrom. 50
9. The method of impregnating fibrous material with oil to produce a journal packing, which comprises the introduction of a predetermined quantity of oil into the chamber of a receptacle, introducing a predetermined quantity of fibrous material into the said chamber, withdrawing the air from the said chamber and simultaneously and automatically compressing the combined mass of oil and fibrous material to cause submersion of the latter in the former. 70
10. The method of impregnating organic fibrous material with oil to produce a journal packing, which comprises the placing of a mass of such material in a chamber, partially evacuating the air from said chamber, introducing oil into the said chamber and thereafter resuming the evacuation of air from the said chamber and simultaneously and automatically effecting pressure upon the said fibrous material previously placed in said chamber. 75
11. The method of impregnating fibrous material with a liquid, which consists in gradually immersing a batch of such material in a mass of liquid, the speed of immersion being proportional to the normal rise of air bubbles through the said liquid to the surface thereof whereby the entraining of air globules within the body of the said material below the surface of the liquid is avoided. 80
12. The method of producing a journal box packing, which consists in gradually immersing a batch of fibrous material in a bath of liquid lubricant, the speed of immersion being proportional to the normal rise of air bubbles through the lubricant to the surface thereof whereby the entraining of air globules within the body of the material below the surface of the lubricant is avoided and a substantially saturated product thereby produced. 85
13. The method of producing journal box packing, which consists in gradually immersing a batch of suitable fibrous material in a bath of liquid lubricant of predetermined volume, the speed of immersion being commensurate with normal rise of air bubbles through the lubricant to the surface thereof whereby the entraining of air globules within the body of the fibrous material below the surface of the lubricant is avoided and a substantially lubricant-saturated product produced. 90
14. The method of producing journal box packing, which consists in gradually immersing a batch of fibrous material in a bath of liquid lubricant of predetermined volume depending upon the degree of impregnation desired, the speed of immersion being commensurate with the normal rise of air globules through the lubricant to the surface thereof whereby the entraining of air globules within the body of the said material below the surface of the lubricant is avoided and a substantially completely impregnated product produced. 105
15. The method of producing journal box packing, which consists in gradually immersing a batch of fibrous material in a bath of liquid lubricant of predetermined volume, the speed of immersion being commensurate with normal rise of air bubbles through the lubricant to the surface thereof whereby the entraining of air globules within the body of the fibrous material below the surface of the lubricant is avoided and a substantially lubricant-saturated product produced. 110
16. The method of producing journal box packing, which consists in gradually immersing a batch of fibrous material in a bath of liquid lubricant of predetermined volume depending upon the degree of impregnation desired, the speed of immersion being commensurate with the normal rise of air globules through the lubricant to the surface thereof whereby the entraining of air globules within the body of the said material below the surface of the lubricant is avoided and a substantially completely impregnated product produced. 115
17. The method of producing journal box packing, which consists in gradually immersing a batch of fibrous material in a bath of liquid lubricant of predetermined volume depending upon the degree of impregnation desired, the speed of immersion being commensurate with the normal rise of air globules through the lubricant to the surface thereof whereby the entraining of air globules within the body of the said material below the surface of the lubricant is avoided and a substantially completely impregnated product produced. 120
18. The method of producing journal box packing, which consists in gradually immersing a batch of fibrous material in a bath of liquid lubricant of predetermined volume depending upon the degree of impregnation desired, the speed of immersion being commensurate with the normal rise of air globules through the lubricant to the surface thereof whereby the entraining of air globules within the body of the said material below the surface of the lubricant is avoided and a substantially completely impregnated product produced. 125
19. The method of producing journal box packing, which consists in gradually immersing a batch of fibrous material in a bath of liquid lubricant of predetermined volume depending upon the degree of impregnation desired, the speed of immersion being commensurate with the normal rise of air globules through the lubricant to the surface thereof whereby the entraining of air globules within the body of the said material below the surface of the lubricant is avoided and a substantially completely impregnated product produced. 130

15. The method of producing journal box packing, which consists in gradually immersing a batch of fibrous material in a bath of liquid lubricant, the speed of immersion being proportional to the normal rise of air globules through the lubricant to the surface thereof, and subjecting the material while immersed in said lubricant to a squeezing action whereby the entraining of air globules within the body of the fibrous material below the surface of the lubricant is avoided and a lubricant-impregnated material produced.

16. The method of producing journal box packing, which consists in supplying to a container a bath of liquid lubricant, gradually immersing a batch of fibrous material in said lubricant at a speed proportional to the normal rise of air globules through the lubricant to the surface thereof, and then compressing said material against the bottom of said container.

17. The method of producing journal box packing, which consists in supplying a container with a bath of liquid lubricant of predetermined volume, superposing a batch of fibrous material upon said lubricant, gradually causing immersion thereof in said lubricant at a speed proportional to the normal rise of air bubbles through the lubricant to the surface thereof, and then compressing the said material against the bottom of said container, substantially all of the said bath being thereby caused to be absorbed by the said fibrous material.

18. The method of producing journal box packing, which consists in gradually and positively immersing a batch of fibrous material in a bath of liquid lubricant, the speed of immersion being proportional to the normal rise of air globules through the lubricant to the surface thereof whereby the entraining of air globules within the body of said material below the surface of the lubricant is avoided and substantially completely impregnated material produced.

19. The method of producing journal box packing, which consists in immersing a batch of fibrous material in a bath of liquid lubricant without producing appreciable agitation of said lubricant.

20. The method of producing journal box packing, which consists in immersing a batch of fibrous material in a bath of liquid lubricant without producing appreciable agitation of the said lubricant and said material.

21. The method of producing journal box packing, which consists in gradually immersing a batch of fibrous material in a bath of liquid lubricant without producing appreciable agitation of said lubricant, the speed of immersion being proportional to the normal rise of air globules through the lubricant to the surface thereof whereby the entraining of air globules within the body

of the said material below the surface of the lubricant is avoided and substantially completely impregnated material thereby produced.

22. The method of producing journal box packing, which consists in superposing a batch of fibrous material upon a body of liquid lubricant in a closed receptacle, gradually evacuating the air from the said receptacle, and simultaneously effecting immersion of the fibrous material in the said bath at a speed proportional to the escape of air bubbles from the said material.

23. The method of producing journal box packing, which consists in superposing a predetermined quantity of fibrous material upon a predetermined quantity of liquid lubricant in a closed receptacle, effecting gradual evacuation of the air from said receptacle, and effecting a positive descending movement of the said fibrous material into the said lubricant at a speed proportional to the escape of air from the said material.

24. The method of producing journal box packing, which consists in superposing a mass of fibrous material upon a quantity of liquid lubricant in a closed receptacle sufficient to effect the degree of impregnation thereof desired, effecting gradual evacuation of air and other gases from the said receptacle, and simultaneously effecting a gradual decrease in the volume of the interior of said receptacle to thereby effect immersion of the said material in the said lubricant at a rate commensurate with the removal of the air and gas from within the mass of the said material.

25. The method of producing a uniformly saturated fibrous material, which consists in gradually immersing a batch of fibrous material in a bath of liquid, the speed of immersion being maintained in step with the normal uniform rise of the liquid in the batch, whereby the entraining of air globules within the body of the batch and below the surface of the liquid is avoided and a substantially uniformly saturated product produced.

26. The method of producing a uniformly saturated fibrous material, which consists in gradually immersing a batch of fibrous material in a bath of viscous liquid, the speed of immersion being maintained in step with the normal uniform rise of the viscous liquid in the batch, whereby the entraining of air globules within the body of the batch and below the surface of the viscous liquid is avoided and a substantially uniformly saturated product produced.

27. The method of impregnating a mass of fibrous material with a liquid, which consists in slowly compressing said mass of material in a bath of such liquid and causing the gases which are held in the said mass to flow slowly therefrom to facilitate the entry

of the liquid into the pores of the material effected at a rate of speed proportional to that at which absorption of said liquid by 10 of the said mass.

28. The method of impregnating a mass of fibrous material with a liquid, which 5 comprises the gradual removal of gases therefrom by the application of pressure thereto in the presence of such liquid, the removal of said gases from said fibrous mass being effected at a rate of speed proportional to that at which absorption of said liquid by 10 said fibrous mass is effected.

In testimony that I claim the foregoing as my invention I have hereunto signed my name this 11th day of February, 1925.

EDWIN S. PEARCE.
